UNITED STATES PATENT OFFICE.

HARLEY C. MOULTON, OF MEDFORD, MASSACHUSETTS, ASSIGNOR, BY MESNE
ASSIGNMENTS, TO LAWRENCE M. STEIN, OF CHICAGO, ILLINOIS.

BLINDSTITCH-PIPING MACHINE.

Application filed April 14, 1922. Serial No. 552,540.

To all whom it may concern:

Be it known that I, HARLEY C. MOULTON, a citizen of the United States, and resident of Medford, county of Middlesex, State of Massachusetts, have invented an Improvement in Blindstitch-Piping Machines, of which the following description, in connection with the accompanying drawing, is a specification, like characters on the drawing 10 representing like parts.

This invention relates to improvements in blind stitch sewing machines for sewing the edge portion of a superimposed layer upon a base layer of material in which the stitches 15 may be laid in the superimposed layer at a distance well back from the edge of said layer.

More particularly the invention relates to improvements in sewing machines adapted 20 to blind stitch the piped edge of a superimposed layer upon a base layer of material and in which the stitches in the superimposed layer or piping will be wholly concealed.

25 In the usual employment of piping in the manufacture of garments, the piping is usually caused to embrace and enclose the edge of a superimposed layer and is secured to the same by through and through stitching. The edge portion of this superimposed layer is then sewed upon the base layer or layers by lines of stitching. In the production of such lines of stitching the needle is either passed downwardly through 30 the superimposed layer, adjacent the edge of the piping, into the base layer without passing through the base layer, or is passed upwardly through the upper surface portion of the base layer and then through the superimposed layer adjacent the edge of the piping. In either event a line of stitching appears upon the upper surface of the superimposed layer and extends along the edge 35 of the piping. In sewing the piped edge of a superimposed layer upon a base layer of material it is found difficult to cause the line of stitching to follow the edge of the piping at all points and any divergence in this line of stitching from the edge of the 40 piping causes an unsightly appearance. Furthermore, the appearance of such an additional line of stitching is not desirable. In the present invention means are provided to stitch the piped edge to the base layer by 45 rows of stitching in which the loops which

are laid in the superimposed layer are entirely concealed as preferably are also those in the base layer, so that the piped edge presents a more desirable appearance than has heretofore been produced by machine 60 work or is usually produced by hand work.

A further object of the invention is to provide a blind stitch sewing machine for stitching the edge portion of a superimposed layer on a base layer of material 65 with means which will turn or roll up the edge of the superimposed layer as it is guided alongside the path of the needle and to provide means for bending, or otherwise presenting, the underface of the layer 70 in the path of the needle so that the needle will enter and emerge from the under surface of the superimposed layer at a considerable distance from its edge. This is accomplished in the present invention by 75 providing a preferably combined guide and bender in which the guide embraces the edge portion of the superimposed layer adjacent the stitching point and the bender acts to thrust the under face of the layer 80 into the path of the needle.

A further object of the invention is to provide a guide and bender for thus manipulating the edge portion of the superimposed layer which will release said edge portion 85 from its deflected or bent position during the action of the feeding mechanism so that the edge portion of the superimposed layer may be straightened and more easily advanced. This is accomplished by providing 90 an upper guide and bender which is moved into position to present the edge portion of the superimposed layer in the path of the needle by the clamping movement of the work support and presser foot 95 and is automatically released from such position by the separation of the work support and presser foot during the feeding operation.

A further object of the invention is to 100 provide means for adjusting the guiding and bending means in order to provide for the proper manipulation of goods of different character and thickness.

A further object of the invention is to 105 provide a novel type of presser foot having mounted thereon a movable device or devices operable by the relative movement of the work support and presser foot to guide properly the under face of a piped or 110

unpiped edge of the superimposed layer into the path of the needle.

A further object of the invention is to provide a presser foot of the type described with means adapted to permit the free movement of the edge of the superimposed layer during the feeding operation.

A further object of the invention is to provide a novel form of work support which will more effectively permit the manipulation and presentation of the base and superimposed layers to the stitch forming mechanism.

A further object of the invention is to improve the relation between the feeding mechanism, the presser foot and work support which will enable the base and superimposed layers to be more uniformly advanced by the feeding mechanism.

Another object of the invention is to provide a piping machine construction in which the body of the garment to be piped may be supported upon the sewing machine table outside of the arm, thus enabling the goods to be manipulated more freely than in usual machines in which the body of the goods is necessarily placed beneath the arm. This is accomplished by placing the mechanism which presents the piped edge to the needle upon the inner side, that is, toward the arm of the machine, instead of the outer side as in usual constructions, so that the folded over edge which is piped extends outwardly, that is, away from the arm.

Other objects and features of the invention will more fully appear from the following description and the annexed drawings and will be pointed out particularly in the accompanying claims.

The preferred embodiment of the invention is disclosed herein as applied to the type of blind stitch sewing machine for sewing a superimposed layer upon a base layer of material which is illustrated and described in my co-pending application No. 332,025 filed October 20, 1919, which comprises a bed plate, a standard rising therefrom provided with an arm overhanging said bed plate having a head carrying a curved oscillating and laterally vibrating needle and complementary stitch forming mechanism and an upper feeding mechanism actuated by the movement of the take-up mechanism. The work is clamped between a relatively movable presser foot and work support which are normally held in clamping relation, but are separated to release the work by the action of a feeding mechanism. In that machine a suitable bender is reciprocably mounted in the work support and is intermittently actuated to present the base layer in the path of the needle.

Only a sufficient portion of the general type of machine is illustrated in the accompanying drawings to show the manner in

which the present invention is applied thereto.

In the drawings:

Fig. 1 is a side elevation of a portion of the stitch forming mechanism and feeding mechanism of said machine and illustrates particularly the form and relation of the presser foot and work support embodying the present invention;

Fig. 2 is a detail front elevation of the presser foot;

Fig. 3 is a plan view of the presser foot illustrated in Fig. 2;

Fig. 4 is a vertical sectional view on line 4-4, Fig. 3 viewed from the right toward the left;

Fig. 5 is a vertical sectional view on line 5-5, Fig. 3, viewed from the left toward the right;

Fig. 6 is an under plan view of the presser foot and feeding mechanism in assembled position, the adjustable pivotal mounting for the guide and bender being shown in section;

Fig. 7 is a detail rear elevation of the presser foot and work support;

Fig. 8 is a plan view of a preferred form of work support;

Fig. 9 is a front elevation of the work support shown in Fig. 8;

Fig. 10 is a perspective view of a combined guide and bender for the edge of the superimposed layer;

Fig. 11 is a detail transverse sectional view through the combined guide and bender when in stitching position; also showing in section the base layer and the bent-up piped edge of the superimposed layer with the needle therein and also showing in dotted lines the normal position of the edge of the superimposed layer; and,

Fig. 12 is a detail view of the pivotally mounted guide and bender showing in full lines the guide and bender in lowered or feeding position, the base and superimposed layers being shown in section, and also showing in dotted lines the combined guide and bender in stitching position.

The general structure of the sewing machine preferably is of the type above briefly described and illustrated in my co-pending application No. 332,025 above identified of which the needle bar supporting member 1 carries a needle bar 2 having a curved oscillating needle 3 which co-operates with complementary stitch forming mechanism in the form of a hook 4 carried by the usual hook bracket 5 as illustrated in Fig. 1 of the drawing. A presser foot 6 is rigidly secured to the hook bracket 5 and co-operates with a work support 7 which is carried by a standard 8 telescopically mounted in a sleeve 9 and normally sustained in clamping relation to the work support by a helical spring 10. A bender 11 mounted and operating in the

manner disclosed in the aforesaid application serves to present the base layer intermittently into the path of the needle.

The feeding mechanism comprises a 5 horseshoe-shaped feed bar 12, (see Fig. 6), which carries feed dogs 13 and 14 mounted respectively in suitable ways in the presser foot. The feed dogs are given their reciprocating feeding movement through a lever 10 15 which is pivotally connected to said feed bar 12, and the feed dogs are given a vertical oscillating movement through an arm 16 rigidly secured to the rear end of the feed bar 12 which is operated by suitable 15 mechanism as disclosed in the application aforesaid.

In the operation of the machine the work is normally clamped by the work support against the presser foot. After a stitch has 20 been formed in the base or superimposed layer the feed bar is oscillated downwardly to cause the feed dogs to depress the work support out of clamping relation to the presser foot. The feed dog is then given a 25 longitudinal rearward movement which advances the work a distance of one stitch. The feed bar is then oscillated in the other direction bringing the work support again into clamping relation with the presser foot and is then advanced into position to again 30 grasp and feed the work for another stitch.

In the machine disclosed in my prior application rigid guiding means are provided for presenting the edge of the superimposed 35 layer in the path of the needle upon certain of its oscillations, while a lower bender is actuated to present the base layer in the path of the needle during certain other, usually alternate, oscillations of the needle. The machine disclosed in said prior application is more particularly adapted for 40 felling the inturned edge of a superimposed layer upon a base layer of material. The present invention while capable of performing a similar operation is more particularly 45 adapted for use in stitching the piped edge of a superimposed layer upon a base layer of material, or for stitching down the edge portion of a superimposed layer of heavy 50 material upon a base layer of material.

In the manipulation of piped edges and the edges of heavy material, difficulty has 55 been encountered in providing means for properly presenting the under face of the piped edge in the path of the needle and for permitting a sufficiently free feeding movement of the piped edge, and further difficulty has been encountered in providing adequate means to enable seams to pass by the stitch forming means and guiding means.

The present invention contemplates the provision of a novel guiding and bender mechanism which will roll up the piped edge of the superimposed layer and present 60 the under face of said layer in the path of

the needle during the formation of the stitch in such superimposed layer and which will operate after the stitch is formed to release the turned-up edge portion from its distorted position during the feeding movement of the work. 70

More specifically the invention consists in providing a blind stitch sewing machine having a rigid presser foot and a co-operating yieldable work support to clamp the 75 work therebetween and which is operated by the feeding mechanism with a movable combined guide and bender which engages the edge portion of the superimposed layer and is operable by the relative movement of 80 the work support and presser foot to clamp the position to bend the under face of the turned-up edge portion of the superimposed layer into the path of the needle during the formation of the stitch in 85 the superimposed layer and to release the turned-up portion from its distorted position during the feeding operation. In order to accomplish this function a special form of presser foot is provided which, as 90 illustrated herein, comprises a body 17 having upwardly extending ears 18 and 19 by which it is secured to the hook bracket, and a forwardly extending toe 20 which projects from the outside of the presser foot, that 95 is to say, the side farthest away from the sewing machine arm as distinguished from usual presser feet in this type of machine which project from the inner side of the body of the presser foot. By this construction the 100 body of the garment may be placed upon the sewing machine table outside of the sewing machine arm and the folded-over piped edge portion carried beneath the arm with the edge presented to the guiding mechanism 105 which will hereinafter be described.

The presser foot is provided with a channel 21 extending upwardly from its under face forming a guide-way for the feed dog 13. A shoe 22, extending rearwardly from 110 the bottom of the presser foot, engages the outer side of the feed dog 14 and serves as a guide for the feed dog and also acts in conjunction with the under face 23 of the heel of the presser foot and the wall 24 of 115 the guide-way 21 to strip the goods from the feed dogs 13 and 14 when they are raised before being advanced to work engaging position.

The usual needle plate 25, which is secured to the under side of the presser foot, extends laterally across the line of stitching and has a curved upper surface 26 corresponding to the arc of reciprocation of the needle extending to the throat 27. The heel portion of the presser foot has a curved surface 28 which in effect forms a continuation of the surface 26 and serves to support the needle after its passage through the work and thereby to prevent its deflection. 120 125 130

The edge of the needle plate 25 is provided with an upwardly extending flange which serves as a guide for the side of the needle in the stroke in which it penetrates the superimposed layer as is usual in blind stitch sewing machines of this type.

A guiding member 29, which desirably is pivotally secured to the front end of the toe 20 by a screw 30, is provided with an upwardly extending, preferably curved, guiding flange 31 to turn up and roll up the piped edge of the superimposed layer as it approaches the stitching point. The turned-up portion is thereafter engaged by a combined guide and bender which operates in a manner hereinafter described to bend the under face of said turned-up edge portion at a distance from the edge thereof into the path of the needle.

The combined guide and bender which is illustrated in detail in Figs. 5, 10, 11 and 12, comprises a movable member having a free end or shoe 32 which rests upon the superimposed layer and an arm 33 which is pivotally and adjustably mounted upon a stud 34 seated in the ear 18 of the presser foot. By reason of this construction the pivotally mounted movable member will be raised by the work support when the latter is released by the feeding mechanism and co-operates with the presser foot to clamp the work during the formation of the stitch and said movable member or shoe will descend by gravity when the work support is depressed by the action of the feed dog preliminary to the action of said dog to feed the work. The upward movement of the movable member or shoe 32 is limited by a plate 35 which is secured to the presser foot and extends over the rear portion of said movable member.

The movable member or shoe 32 extends forwardly beyond the throat of the presser foot and is provided with a curved face which lies at an angle to the direction of the line of stitching and approaches closely to the path of the needle adjacent the stitching point. The lower portion of the movable member or shoe 32 has a relatively thin projection or bender 36, adjacent the stitching point, which is adapted to engage the upper face of the superimposed layer at a distance from its edge and to force the lower face of the turned-up portion of the superimposed layer into the path of the needle when said member is held in its normal raised position by the action of the work support. The movable member is beveled at the rear of the bender portion to provide a clearance 36* for the edge of the superimposed layer beyond the stitching point.

The movable member or shoe 32 is provided with a preferably adjustable guide 35 which overlies and embraces the edge of the

superimposed layer and serves to limit the width to which the edge portion thereof is turned up. A preferred form of edge guide comprises a plate or finger 37 which is adjustably secured by screw and slot connection 38 to an inclined upper face upon the shoe 32. This guide overlies and embraces the turned-up edge of the superimposed layer in advance of and at the stitching point. By suitably adjusting this edge guide it may be properly set to manipulate the plain edge or the piped edge of the superimposed layer of any desirable material so that the line of stitching in said superimposed layer will be laid at a predetermined distance from its edge whereby the line of stitching when completed will be entirely concealed.

It will be obvious that when the combined guide and bender above described is in normal position in which the stitch is being made in the superimposed layer the turned-up edge will be distorted at the stitching point so that feeding of the goods will be difficult, particularly where a relatively stiff piped edge is being sewed to the base layer. By reason, however, of its pivotal mounting the combined guide and bender will drop down and swing away from normal position when the work support is depressed by the feeding mechanism preparatory to the feeding movement. When the bender is swung away from its normal position the distorted portion of the superimposed layer is permitted to straighten and to be advanced easily during the feeding movement.

In order to permit the bender and guide to operate properly upon goods of different thicknesses means are provided for laterally adjusting the combined bender and guide. Any suitable means may be provided for accomplishing this purpose. As illustrated herein the arm 33 of the movable member 32, which is pivoted upon the stud 34, is provided with a relatively large circular aperture surrounding said stud and an eccentric sleeve 39 fitting said aperture is pivotally mounted upon the stud 34. The sleeve 39 preferably is provided with an enlarged toothed portion or head 40 which may be conveniently grasped to adjust the eccentric sleeve, and a spring pawl 41 engages the teeth of the head 40 to retain the sleeve in adjusted position.

Obviously the rotary adjustment of the sleeve will position the member 32 toward and from the path of the needle so that a proper relation between the bender and needle path may be obtained for goods of different thicknesses.

Desirably the forward heel portion of the presser foot is cut away to provide a relatively large clearance space 42 beyond the stitching point, this cut-away portion being

opposite the cut-away portion 36 of the movable member, so that the turned-up edge of the superimposed layer is not impeded as it passes from the stitching point.

5 It will be noted that a free space 44 is provided between the feed dogs 13 and 14 to avoid any obstruction to the passage of the piped edge or seams in the work.

10 In order to enable the work to be fed more uniformly and also to assist in presenting it to the stitching mechanism the work support preferably is so constructed that a smaller area of the work is engaged by the portion of the work support which 15 co-operates with the toe portion 20 of the presser foot than that which co-operates with the movable member 32.

15 As illustrated herein the work engaging face 45 of the work support, which co-operates with the toe portion, is extended forwardly and is approached by a rather long inclined surface 46, while the central face 47 of the work support, which is immediately in front of the stitching point, is considerably shorter and is approached by an inclined surface 48 of a steeper inclination than that of the surface 46. The inner face 49 of the work support, which co-operates with the movable member or shoe 32, 20 is of considerably greater length and is approached by a much more abruptly inclined surface 50. The surface 49 desirably lies in a slightly lower plane than the faces 45 and 47 so that the additional thickness of material, due to the superimposed layer, 25 will not interfere with the clamping action upon the base layer. The junction between the approaching surfaces 47 and 49 preferably presents a shoulder which aids somewhat in guiding the work to the stitch forming mechanism. By reason of the work support construction above described both the superimposed layer and base layer may 30 be effectively clamped during the stitching operation and the work may be more evenly fed and easily guided during the feeding movement.

35 In the operation of the machine the body of the material to be piped is laid upon the sewing machine table beyond the head of the machine and the base layer and turned-over piped edge are presented to the stitch forming mechanism, the edge of the layer being slightly turned up by the operator 40 and pressed against the guide 31 on the toe of the presser foot. As the feeding mechanism advances the work, the turned-up edge portion enters into the space between the curved face of the movable member or shoe 32 and the edge guide 37, and the upward movement of said edge is limited thereby. When the work support is raised by its 45 spring into clamping relation to the presser foot the movable member or shoe, which constitutes the combined guide and bender,

is raised and the bender thrusts the under face of the turned-up portion of the superimposed layer into the path of the needle as it reciprocates in a path adjacent to the upwardly extending flange upon the 70 needle plate. After passing through the superimposed layer the needle is supported by the curved portion 28 of the heel of the presser foot.

75 Upon the withdrawal of the needle and formation of the stitch the work support is depressed by the initial action of the feeding mechanism and the movable member 32 drops down thereby removing the bender portion of said member from the position 80 into which it deflects the superimposed layer into the path of the needle, thus permitting the piped edge to straighten and to be readily advanced by the action of the feeding mechanism.

85 The clearance in the heel of the presser foot and that in the movable member at the rear of the bender portion permits the edge of the superimposed layer to pass along freely, during the feeding movement. At 90 the end of the feeding movement the feed dogs are raised thus again permitting the work support to rise and clamp the work against the presser foot and thereby again to force the movable member 32 upwardly 95 so that its bender portion deflects another portion of the turned-up edge of the superimposed layer into the path of the needle.

95 In the usual operation of the machine the 100 needle is given both an oscillating and a laterally vibrating movement so that one row of stitches is formed in the superimposed layer and another row in the base layer, the base layer being presented in the other path of the needle for such purpose by the reciprocating bender 11 which is operated in the usual manner. By reason of this construction the stitches are laid in the superimposed layer or piping at a distance well 105 back from the edge thereof and the stitches in the superimposed layer may be so positioned that the entire seam is concealed by the projecting edge of the superimposed layer or piping when the stitches are finally set.

110 115 It will be understood that the embodiment of the invention disclosed herein is of an illustrative character and is not restrictive and that various changes in form, construction and arrangement of parts may be made within the spirit and scope of the following claims.

120 Having thus described my invention, what I claim as new, and desire to secure by Letters Patent, is:

125 1. In a blind stitch sewing machine for sewing the edge portion of a superimposed layer upon a base layer of material, comprising a needle and complementary stitch forming mechanism, a relatively movable 130

- work support and presser foot, means acting to cause said work support and presser foot to clamp the work therebetween, feeding mechanism operable to feed the work and to cause said work support and presser foot to release the work during the feeding operation and a movable member engaging the edge portion of the superimposed layer operable by the relative movement of the work support and presser foot to clamping position to present the under face of the edge portion of said superimposed layer in the path of the needle during the formation of the stitch in said layer.
- 15 2. In a blind stitch sewing machine for sewing the edge portion of a superimposed layer upon a base layer of material, comprising a needle and complemental stitch forming mechanism, a relatively movable work support and presser foot, means acting to cause said work support and presser foot to clamp the work therebetween, feeding mechanism operable to feed the work and to cause said work support and presser foot to release the work during the feeding operation and a movable member engaging the edge portion of the superimposed layer operable by the relative movement of the work support and presser foot to clamping position to present the under face of the edge portion of said superimposed layer in the path of the needle during the formation of the stitch in said layer and means for adjusting said movable member toward or from the line of stitching.
- 30 3. In a blind stitch sewing machine for sewing the edge portion of a superimposed layer upon a base layer of material, comprising a needle and complemental stitch forming mechanism, a relatively movable work support and presser foot, means acting normally to cause said work support and presser foot to clamp the work therebetween, feeding mechanism operable to feed the work and to cause the work support and presser foot to release the work during the feeding operation and a movable member pivotally mounted upon the presser foot having its free end resting upon and engaging the edge portion of the superimposed layer and operable by the relative movement of the work support and presser foot to clamping position to present the under face of the edge portion of the superimposed layer in the path of the needle during the formation of the stitch in said layer,
- 45 4. In a blind stitch sewing machine for sewing the edge portion of a superimposed layer upon a base layer of material, comprising a needle and complemental stitch forming mechanism, a relatively movable work support and presser foot, means acting normally to cause said work support and presser foot to clamp the work therebetween, feeding mechanism operable to feed the work and to cause the work support and presser foot to release the work during the feeding operation and a movable member having a guide embracing the edge of the superimposed layer acting to roll up said edge and provided with a bender portion resting upon said superimposed layer and at its end engaging the rolled up edge portion and operable by the relative movements of the work support and presser foot to present the under surface of the edge portion of said superimposed layer into the path of the needle during the formation of the stitch in said layer and to permit said edge portion to straighten during the feeding movement.
- 60 5. In a blind stitch sewing machine for sewing the edge portion of a superimposed layer upon a base layer of material, comprising a curved oscillating and laterally vibrating needle and complemental stitch forming mechanism, a relatively movable work support and presser foot acting normally to clamp the work therebetween, feeding mechanism operable to feed the work and to cause the work support and presser foot to release the work during the feeding operation and a movable member having a guide embracing the edge of the superimposed layer acting to roll up said edge and provided with a bender portion resting upon said superimposed layer and at its end engaging the rolled up edge portion and operable by the relative movements of the work support and presser foot to present the under surface of the edge portion of said superimposed layer into the path of the needle during the formation of the stitch in said layer and to permit said edge portion to straighten during the feeding movement and means for adjusting said movable member toward and away from the line of stitching.
- 75 6. In a blind stitch sewing machine for sewing the edge portion of a superimposed layer upon a base layer of material, comprising a curved oscillating and laterally vibrating needle and complemental stitch forming mechanism, a relatively movable work support and presser foot acting normally to clamp the work therebetween, feeding mechanism operable to feed the work and to cause the work support and presser foot to release the work during the feeding operation and a movable member having a guide embracing the edge of the superimposed layer acting to roll up said edge and provided with a bender portion resting upon said superimposed layer and at its end engaging the rolled up edge portion and operable by the relative movements of the work support and presser foot to present the under surface of the edge portion of said superimposed layer into the path of the needle during the formation of the stitch in said layer and to permit said edge portion to straighten during the feeding movement and means for adjusting said movable member toward and away from the line of stitching.
- 90 7. In a blind stitch sewing machine for

imposed layer and a bender engaging said layer, adjacent the stitching point, acting to force the under face of said superimposed layer into the path of the needle at the stitching point and having a clearance beyond said bender in co-operative relation to the clearance in said presser foot and feeding mechanism operable to cause said work support to release the work during the feeding operation.

12. In a blind stitch sewing machine for sewing the edge of a superimposed layer upon a base layer of material, comprising a needle and complementary stitch forming mechanism a relatively movable work support and presser foot, means acting to cause the work support and presser foot to clamp the work therebetween, feeding mechanism having work engaging members engaging respectively the base layer and the superimposed layer upon opposite sides of the line of stitching at a distance from the edge of the superimposed layer and acting during the feeding movement to cause the work support and presser foot to release the work, a member pivotally mounted on said presser foot having its free end resting upon the superimposed layer and guiding means embracing the edge of said layer and operable by the relative movement of the work support and presser foot to clamping position to roll up the edge portion of said superimposed layer and to present the under surface thereof in the path of the needle.

13. In a blind stitch sewing machine for sewing the piped edge of a superimposed layer upon a base layer of material, comprising a curved oscillating needle and complementary stitch forming mechanism a reciprocable work support and feeding mechanism, a movable guide and bender for the piped edge of the superimposed layer operable by the reciprocation of said work support alternately to bend the under face of the piped edge into the path of the needle and to permit the piped edge to straighten during the feeding movement.

14. A presser foot for blind stitch sewing machines for sewing the edge portion of a superimposed layer upon a base layer of material, comprising a member freely pivoted upon said presser foot to swing below the plane of the work engaging surface of the presser foot and provided with a guide to embrace the edge of the superimposed layer and with a bender portion underlying said guide.

15. A presser foot for blind stitch sewing machines for sewing the edge portion of a superimposed layer upon a base layer of material, comprising a member freely pivoted upon said presser foot to swing below the plane of the work engaging surface of the presser foot and provided with a guide to embrace the edge of the superimposed layer

and with a bender portion underlying said guide and means for adjusting said guide.

16. A presser foot for blind stitch sewing machines for sewing the edge portion of a superimposed layer upon a base layer of material, comprising a member freely pivoted upon said presser foot to swing below the plane of the work engaging surface of the presser foot and provided with a guide to embrace the edge of the superimposed layer and with a bender portion underlying said guide, the heel portion of said presser foot having a recess at the rear of the stitching point to provide a clearance for the edge portion of the superimposed layer.

17. A presser foot for blind stitch sewing machines for sewing the edge portion of a superimposed layer upon a base layer of material, comprising a member freely pivoted upon said presser foot to swing below the plane of the work engaging surface of the presser foot and provided with a guide to embrace the edge of the superimposed layer and with a bender portion underlying said guide, said member and the heel portion of said presser foot being provided with co-operating recessed portions at the rear of the stitching point to provide a clearance for the edge portion of the superimposed layer.

18. In a blind stitch sewing machine for sewing the edge portion of a superimposed layer upon a base layer of material comprising stitch forming mechanism, feeding mechanism and a presser foot having a toe portion provided with a laterally extending needle plate having a throat engaging said base layer and guiding means engaging the superimposed layer; a work support co-operating with said presser foot having a clamping face of shorter length co-operating with the toe portion of the presser foot and its needle plate than that which co-operates with the guiding means for the superimposed layer, the surface of the work support which co-operates with the guiding means for the superimposed layer lying in a lower plane than that which co-operates with the toe portion of the presser foot and its needle plate, whereby a substantially uniform clamping of the base and superimposed layers is produced and the shoulder formed by the adjacent edges of the clamping surfaces of the work support aids in guiding the edge of the superimposed layer.

19. In a blind stitch sewing machine for sewing the edge portion of a superimposed layer upon a base layer of material comprising stitch forming mechanism, feeding mechanism and a presser foot having a toe portion provided with a laterally extending needle plate having a throat engaging said base layer and guiding means engaging the superimposed layer; a work support co-operating with said presser foot having a

clamping face of shorter length co-operating with the toe portion of the presser foot and its needle plate than that which co-operates with the guiding means for the superimposed layer, and inclined faces leading to the work clamping face of the work support of which the inclined face leading to the clamping face which co-operates with the toe portion of the presser foot is of more gradual inclination than that which co-operates with the guiding means for the superimposed layer.

20. In a blind stitch sewing machine for sewing the edge portion of a superimposed layer upon a base layer of material comprising stitch forming mechanism, feeding mechanism and a presser foot having a toe portion provided with a laterally extending needle plate having a throat engaging said base layer and guiding means engaging the superimposed layer; a work support co-

operating with said presser foot having a bender aperture opposite the throat in said needle plate and having a work clamping face co-operating with said presser foot and needle plate and also having a work clamping face located in a lower plane co-operating with said guiding means for the superimposed layer, inclined work supporting surfaces leading to said clamping faces including a gradually inclined surface in advance of the work clamping portion which co-operates with the presser foot, a more steeply inclined surface located in advance of the bender aperture and a still more abruptly inclined surface leading to the work clamping face which co-operates with the guide for the superimposed layer.

In testimony whereof, I have signed my name to this specification.

HARLEY C. MOULTON.
